(57) **CLAIM**

The ornamental design for an insect eliminating device, as shown and described.

DESCRIPTION

FIG. 1 is a perspective view of an insect eliminating device showing my new design;

FIG. 2 is a top view thereof;

FIG. 3 is a bottom view thereof;

FIG. 4 is a front view thereof;

FIG. 5 is a rear view thereof;

FIG. 6 is a side view thereof;

FIG. 7 is an opposite side view thereof;

FIG. 8 is a perspective view of an insect eliminating device with a cap portion removed showing my new design;

FIG. 9 is a top view thereof;

FIG. 10 is a bottom view thereof;

FIG. 11 is a front view thereof;

FIG. 12 is a rear view thereof;

FIG. 13 is a side view thereof; and,

FIG. 14 is an opposite side view thereof.

The broken lines showing the internal grid, the charging port, the switch and the opening in the top illustrate environmental structure and form no part of the claimed design.
